UNITED STATES PATENT OFFICE.

JOHN HEBERLING, OF ROCHESTER, NEW YORK, ASSIGNEE OF ONE-HALF TO HAROLD R. SIMMS, OF ROCHESTER, NEW YORK.

PRINTING-MACHINE.

1,338,386.

Specification of Letters Patent. Patented Apr. 27, 1920.

Application filed November 29, 1918. Serial No. 264,675.

To all whom it may concern:

Be it known that I, JOHN HEBERLING, a citizen of the United States, and resident of Rochester, in the county of Monroe and State of New York, have invented certain new and useful Improvements in Printing-Machines, of which the following is a specification.

The present invention relates to printing machines, and more particularly to the type in which a plurality of type lines are adapted to be brought selectively into coöperation with a platen or impression member, an object of this invention being to provide for inclosing a printing member which is rotatable about two axes one at an angle to the other, its rotation about one axis being to select a type line for coöperation with the platen or impression member, and its rotation about the other axis being for the purpose of printing and feeding the work. Another object of the invention is to provide, in a printing machine of the printing wheel type mentioned, a simple operating means for turning the wheel about its axis to select the printing line, said operating means being controllable from the exterior of the casing. Still another object of the invention is to provide a rupturing means which will feed the work to a printing couple. A further object of the invention is to provide a rupturing means separate from the printing and feeding couple to break the surface of the work in advance of the feeding. A still further object of the invention is to provide a rupturing means which will permit the breaking of the work as the latter moves under the action of the printing and feeding couple. A still further object of the invention is to provide, in connection with a printing and feeding couple, a rupturing means which will rupture the work, prior to the printing operation, and feed the work to the printing and feeding couple, the feeding action of the rupturing means being thereafter rendered ineffective to permit the printing and feeding couple to move the work through the rupturing means.

To these and other ends the invention consists of certain parts and combinations of parts, all of which will be hereinafter described, the novel features being pointed out in the appended claims.

In the drawings:

Fig. 1 is a view in side elevation of a printing machine constructed in accordance with this invention;

Fig. 2 is a plan view of the machine;

Fig. 3 is a vertical section of the machine;

Fig. 4 is a detail view showing the rotary printing member and the rotary frame on which the printing member is mounted to turn, the said frame being partially broken away;

Fig. 5 is a section on the line 5—5, Fig. 3, showing the normal position of the printing member;

Fig. 6 is a view similar to Fig. 5, showing the printing member in coöperation with the rotary platen or impression member;

Fig. 7 is a section on the line 7—7, Fig. 3 showing the connection between the rotary frame which carries the printing member, 75 and the platen carrying shaft for the purpose of turning the paper rupturing means which is geared to the platen carrying shaft;

Fig. 8 is a view similar to Fig. 7, showing another position of the connection between the rotary frame carrying the printing wheel and the platen carrying shaft;

Fig. 9 is a section on the line 9—9, Fig. 5;

Fig. 10 is a detail view of a part of the connection between the rotary frame carrying the printing wheel and the platen carrying shaft;

Fig. 11 shows in enlarged form the manner in which the printing is accomplished;

Fig. 12 is a sectional view on the line 12—12, Fig. 11, showing the work on a still larger scale;

Fig. 13 is a view of the under side of the machine showing the connection between the paper rupturing means and the rotary frame that carries the printing wheel, together with the lever which controls such connection, the lever being shown in the position in which the paper rupturing means is in an inoperative position;

Fig. 14 is a view similar to Fig. 13, showing the lever adjusted to a position where it effects the operation of the paper rupturing means to cause the latter to feed the work to the printing and feeding couple;

Fig. 15 is a view similar to Figs. 13 and 14 showing the lever adjusted to still an-

other position where it is automatically shifted to effect the rupturing of the work under the feeding action of the printing and feeding member;

5 Fig. 16 is a detailed view of the under side of the upper or overhanging part of the casing; and

Fig. 17 is a fragmentary view showing a section on the line 17—17, Fig. 15.

10 The invention is herein illustrated as embodied in a machine designed for printing the exact amount in checks or other negotiable instruments, but it will be understood that the invention is not limited to machines 15 of this type. The construction illustrated embodies a casing having a base portion 1 formed with a work support 2 and having an overhanging portion 3 secured to the base portion at the rear of the work support 2, the overhanging portion being spaced to provide a forwardly opening work receiving slot through which the work may be passed. The printing mechanism embodies a printing couple, in this instance, 20 in the form of a type wheel 5 mounted in the overhanging portion 3 of the casing, and a platen or impression member 6 mounted in the base portion 1 of the casing, this printing couple acting not only to print but to feed the work.

30 The printing member 5 is, in this instance, in the form of a type wheel rotatable upon a shaft 7 which, in turn, is mounted on a frame 8, the latter being turnable about an axis which is at right angles to the axis of turning of the printing wheel 5, the axis of the printing wheel not intersecting the axis of the shaft 8, but being situated in a plane to one side of the axis of the frame 8. The printing lines 9 which are of different lengths as is common in this art to print different words, may be turned selectively to a printing position, and when in this position the arcs formed by their printing faces will be concentric with a center situated at the axis of the turning of the rotary frame 8, the purpose of this being to permit the printing face at printing position to coöperate with the platen 6 through- 40 out the entire length of said face with an even pressure.

50 The frame 8 on which the printing wheel 5 is mounted embodies a central portion having an opening in which the printing wheel 5 is arranged, and also embodies a bearing portion 10 turning in the front wall of the overhanging casing 3 and a hollow bearing portion 11 turning in the rear wall of the upper part of the casing and projecting to 55 the rear of said casing. On this projecting portion of the hollow bearing portion 11 a disk 12 is arranged, said disk having an operating arm 13 projecting from its periphery and carrying a handle by which the rotary frame 8 may be turned. This handle,

in this instance embodies a grip portion 14 rotatable upon a movable axle in the sleeve portion 15, which is rigidly secured to the arm 13. In this sleeve portion is a latch or plunger 16 which, at its outer end is connected to the grip portion 14, and at its inner end projects from the inner face of the arm 13, to provide a locking device for entering into a pocket or recess 17 formed in the base portion 1 below the disk 12. This locking device serves to point out the initial or starting position of the printing member which, before it can be turned, must be released by withdrawing the latch or plunger 16 from the pocket 17, the locking device re-entering the said pocket upon the completion of one rotation of the printing member. The purpose of this locking device is to make provision for insuring that the printing member will not be in engagement with the platen when it is desired to rotate such printing member to bring another type line to printing position.

55 Operation of the printing member 5 from the exterior of the casing may be obtained by providing the printing member with a gear wheel 18 on one side thereof meshing with a pinion 19 on the frame 8, said pinion 19, in turn, meshing with a crown gear 20 which is secured to a shaft 21 extending through the hollow shaft or bearing portion 11 of the frame 8 to the exterior of the machine, so that the shaft 21 and the hollow bearing portion 11 have a common axis. On the exterior of the machine, the shaft 21 100 is provided with a dial 22 and a thumb wheel 23, the latter serving to permit the dial and the printing wheel 5 to be turned relatively to the frame 8 for the purpose of selecting one of the lines on the printing 105 wheel for printing operation. When this selection takes place, the printing wheel 5 and the rotary frame 8 are in positions shown in Figs. 3 and 5 of the drawings, that is, the printing wheel is out of coöperation 110 with the platen 6, and this position is, as before mentioned, determined by the locking device 16 which enters the recess 17 in the base 1 of the frame.

115 The impression member or platen 6 is, in this instance, in the form of a rotary wheel situated below the work plate 2 and operating through a slot or opening 24 in the work plate. Preferably the surface of this platen is roughened, but this roughening is not sufficient to break or cut the paper. It is provided solely for the purpose of producing friction between it and the type faces, which are preferably smooth in order that when the two coöperate the work will be firmly 120 clamped between the two surfaces and move through such engagement. The type also operate through an opening 25 in a plate 26 which is secured to the under side of the overhanging portion 3 of the casing above 130

the work support 2. Support of the platen 6 is obtained by a shaft 27 arranged in bearings 28 in the base portion 1 of the casing of the machine. Owing to the fact that the platen 6 is mounted on a long shaft, the platen has a slight resilient mounting, and when the end of the printing line is reached it co-operates with the end of the type line in such a manner as to prolong the engagement between it and the type line thus acting to space the words from each other without any spacing means being required.

The inking of the printing member may be effected in any suitable manner as by an inking roller 29 arranged on a swinging frame 30 which is pivotally mounted at 31 on a plate 32 acting as a closure for a projecting pocket 33 on the overhanging portion 3 of the casing of the machine. The stop 34 limits the movement of the swinging frame 30 under the action of a spring 35 which normally holds the roller 29 in the path of the type line that is situated at printing position on the swinging frame. This roller is situated on that side of the casing past which the selected type line must travel last before reaching the platen or impression number. The stop 34 is so positioned that only that type line which is concentric with the turning axis of the frame 8 will be engaged by the inking roller, while that line which is diametrically opposite the selective line cannot be engaged, this being due to the fact that the axis of the printing wheel 5 is eccentric with reference to the axis of the turning frame 8.

It will be apparent that a machine has been hereinbefore described as capable of acting as a printing machine without any more elements. It is, however, desirable to provide in printing machines of this type a means for rendering difficult the changing of the printing matter, and to this end suitable means may be embodied in the machine for bruising or rupturing the paper so that the changing of the printing matter will be difficult. In this instance, paper rupturing means is provided which is separate from the printing and feeding couple. This paper rupturing means comprises preferably two cutting members 36 and 37. The cutting member 36 is situated on the overhanging portion 3 of the casing and is preferably in the form of a roller turning about an axis 38 and secured to a plate 39 which is fastened to the under side of the projecting portion or pocket 33 of the overhanging portion of the casing. The roller or cutting member 37 is mounted on a base part 1 of the casing, preferably turning upon a shaft 40 which is supported on a swinging frame 41, said frame being mounted to turn on the platen shaft 27 in order that the cutting wheel 37 will move toward and from the cutting wheel 36, so that the cutting wheels

may be separated for the purpose of permitting the introduction of the work into the machine.

Movement of the cutting wheel 37 toward and from the cutting wheel 36 may be effected by a lever 42 which is pivotally mounted at 43 to the base 1, and has the free end thereof operating on a fixed abutment 44 to be moved into and out of co-operation with a spring or resilient portion 45 formed on the swinging frame 41 for the purpose of effecting the movement of the frame, and thus causing the cutting roller 37 to move toward and from the roller 36. The resiliency is provided in portion 45 in order that the pressure of the roller 37 toward the roller 36 will be yielding.

It is apparent that the printing and feeding couple 5 and 6 will, during the printing and feeding action, move the work through the rupturing means formed by the two cutting rollers 36 and 37, thus causing the rupturing of the paper before the printing takes place. The surfaces of the rupturing wheels are so formed that the paper is ruptured in the manner shown in Figs. 11 and 12, this being due to the fact that the lower rupturing wheel 37 has a number of pyramidal shaped pin point projections, whereas the surface of the cutting device 36 is formed with circumferential grooves receiving such pyramidal shaped pin point projections. The ruptured paper as will be seen by referring to Figs. 11 and 12, has on its printed side a series of raised projections 100 46 perforated at their ends, and when this ruptured portion has passed between the printing couple, the flat surfaces of the type faces depress these perforated raised projections to the plane of the paper as shown 105 at 47 in Fig. 12 of the drawings. At the same time the ink penetrates the perforations as well as covers the surface of the paper between the perforations, and as the perforations are close together any attempt 110 to erase the printed matter will cause the destruction of the paper.

It is apparent that it is desirable to provide some means for feeding the paper in a ruptured condition to the printing members 115 before receiving the first printing operation, so that the first word printed will have a ruptured surface to operate upon. This result is secured, in this instance, by moving the rupturing means so as to feed the paper 120 slightly on the first operation of the printing member upon the printed check. The mechanism for securing this result comprises, in this instance, a pinion 48 on the rupturing wheel 37 meshing with the idle pinion 49 on the frame 41. This idle pinion, in turn, meshes with the pinion 50 on the platen 6 which, in turn, is secured to the shaft 27. On this shaft is arranged a gear 51, this gear being carried by a sleeve 130

52 keyed at 53 to turn with the shaft 27, but being adapted to move axially of said shaft. The gear 51 is, in turn, adapted to mesh with a gear segment 54 which is preferably 5 provided at 55 to a disk 56. A spring 57 acts on the gear segment 54 to normally hold said segment against a stop 58, the purpose of this yielding being to permit the yielding of the teeth of the segment 54 when 10 the latter engages the gear 51, should the proper meshing of the teeth of the two parts not occur during their first engagement. The disk 56 is, in this instance, formed of two segments clamped to the hollow bearing 15 portion 11 of the turning or rotary frame 8, so that when said frame is turned by the end piece 14, the disk 56 will be turned. This disk 56 also carries a cam surface 58 which is adapted to coöperate with one face 20 of the gear 51 in order to move said gear out of the path of rotation of the gear segment 54.

Movement of the gear segment 51 into the path of the gear segment 54, as well as the 25 movement of the cutting wheel 37 into co-operation with the gear 36, is effected preferably by a single device in the form of a lever 59 pivoted at 43 on the pivot of the lever 42 and having an operating portion 30 60 extending through a slot 61 in the base 1. This lever has a lost motion connection with the lever 42 preferably by a pin 62 on the lever 42, and a bifurcated projection 63 on the lever 59. The lever 59 also has connection with the gear 51, and this is effected 35 through a projection 64 on the upper face of the lever 59 operating in an annular groove 65 formed in the sleeve 52.

When the machine is ready to receive the 40 work or check the lever 59 is swung to its extreme forward position, as shown in Fig. 13, thus holding the gear 51 out of the path of the segment 54, and permitting the swinging frame 41 to drop downwardly on to the surface 44. After the check has been properly positioned in the machine against the gage 66, which is adjustable on the base frame 1 through a slot 67 and a set screw 68, the lever 59 is swung to the extreme rear end 45 of the slot 61, as shown in Fig. 15, thus throwing the gear 51 in the path of the gear segment 54, and causing the lever 42 to move between the surface 44 and the swinging frame 41, elevating the frame so 50 as to carry the rupturing wheel 37 into co-operation with the cutting wheel 36. The type wheel 5 is then turned to select a desired line of type through the indicating dial 22, which coöperates with a fixed 55 pointer 22^a on the casing. Upon the selection of the desired word, the latch 16 is withdrawn from the recess 17, and the rotary frame 8 is turned, the type wheel and its shaft 21 turning with said frame. The 60 65 selected line will lie on the side of the ma-

chine opposite the inking roller 29, and will move toward and over said inking roller to the platen 6, where it will engage the work and cause the printing of the selected line as well as the feeding of the work. During 70 the first part of the movement of the rotary frame 8, the gear segment 54 will enter into engagement with the gear 51 and turn such gear 51, causing the turning of the shaft 27 and the turning of the paper rupturing 75 means to cause the paper to be broken or ruptured, and then fed to a point above the rotary platen 6. After this feeding of the paper and before the printing wheel co-operates with the platen, the cam surface 80 57 on the segmental disk 56 will coöperate with the rear face of the gear 51 and shift the latter axially out of the path of the disk segment 56, at the same time causing a shifting of the lever 59 to the position shown 85 in Fig. 15, so that any further movement of the rotary frame 8 does not produce any movement in the paper rupturing means through the disk 56, the successive operations of the printing member to complete 90 the printing of any one check depending upon the printing couple for the feeding of the check, and the movement of the check through the paper rupturing means. After the check has been completed the lever 59 95 is shifted to the forward end of the slot, as shown in Fig. 13.

From the foregoing it will be seen that there has been provided in a printing machine of the type having a printing wheel, 100 rotatable about two axes at right angles to each other, a printing wheel operable from the exterior of a casing which incloses the wheel. A rupturing means has been provided separate from the printing couple for 105 feeding the work to the couple. This couple also acts to move the work through the rupturing means. The rupturing means acts as a clamp for holding the work in printing position and is operable to release 110 the work. After the rupturing means shifts the ruptured work to the printing couple its feeding action is automatically stopped and the printing couple feeds the work through the rupturing means, this feeding 115 being assisted by the gearing between the platen and the lower rupturing wheel, the peripheral speeds of the platen and the lower rupturing wheels being the same so that no strain is imposed on the work.

What I claim as my invention and desire to secure by Letters Patent is:—

1. A printing machine comprising a casing formed with a forwardly opening check receiving slot, a frame mounted to turn in the casing above the slot and having a portion extending to the exterior of the casing, a printing member mounted to turn on the frame about an axis at an angle to the turning of the frame, and operating means for 125 130

- the printing member having a portion on the exterior of the casing and also embodying a shaft with an axis common to the axis of turning of the frame.
- 5 2. A printing machine comprising a frame mounted to turn about a suitable axis, a printing member turnable on a frame about an axis at an angle to the axis of the turning of said frame, and operating means for 10 the printing member having a shaft with its longitudinal axis common to the axis of turning of the frame.
3. A printing machine comprising a rotary frame having a hollow bearing portion, a printing wheel mounted to turn on the frame about an axis at an angle to the axis of turning of the frame, a shaft extending through the hollow bearing portion of the frame and having a driving connection with the printing member, and indicating means for determining the position of the printing member on the frame having an indicating member connected with the shaft which turns the printing member.
- 25 4. A printing machine comprising a casing provided with a work receiving slot, an impression member arranged at the lower side of the slot, a frame rotatable in the casing above the slot, and having a hollow bearing portion extending to the exterior of the casing, a printing wheel rotatable upon said rotary frame about an axis at an angle to the axis of rotation of the frame, a shaft turnable in said bearing portion of the 30 rotary frame and having a driving connection with the printing member, indicating and operating means connected with said shaft for shifting and determining the position of the printing member on the rotary frame within the casing, and operating means for the rotary frame arranged on the exterior of the casing.
5. A printing machine comprising a casing provided with a work receiving slot, an impression member arranged at the lower 45 part of the slot, a rotary frame arranged within the casing above the slot and having a portion extending to the exterior of the casing, an operating arm connected to said portion and carrying a latch arranged to operate with the casing to determine the normal position of the frame, a printing member rotatable on the frame about an axis at an angle to the axis of turning of the frame, and operating means for the printing member controllable from the exterior of the casing and having a shaft with its longitudinal axis common to the axis of turning of the rotatable frame.
- 50 6. A printing machine comprising an impression device, a rotary printing member, a frame rotatable in a complete circle and on which said rotary printing member is rotatable about an axis at an angle to the axis of turning of said rotary frame, a sta- 100 tionary casing inclosing said frame and printing member, an operating member for turning said printing member arranged on the exterior of the casing, and a latch mounted on said operating member and 70 movable into engagement with the casing to determine the normal position for the rotary frame in which the printing member lies out of coöperation with the impression device. 75
7. A printing machine comprising a platen, a printing member having a plurality of lines of type thereon of different lengths and also having a movement independently of the platen to select one of 80 the typed lines for coöperation with the platen, said platen and printing member having a simultaneous movement to print the work and feed the latter different distances according to the selected type line, 85 paper rupturing means, and means for operating the paper rupturing means to rupture the work an amount corresponding to the selected type line, said means being inoperative during the selective movement of 90 the printing member.
8. A printing machine comprising a platen, a printing member having a plurality of lines of type thereon and also having a movement independently of the 95 platen and out of coöperation therewith to select one of said type lines for coöperation with the platen, paper rupturing means for rupturing the work prior to a printing action, and mechanism for operating the 100 paper rupturing means to cause the latter to feed work in the direction of the line of printing between and relatively to the printing member while said printing member and platen are out of coöperation, and for effecting coöperation between the platen and the printing member. 105
9. A printing machine comprising a printing member provided with a plurality of lines of type of different lengths and 110 having two movements, one transversely of the type lines and relatively to the platen to select a type line for printing and the other to print the work and feed the latter different distances according to the length 115 of the selected type line, a platen for coöperation with the selected line of type, movable with the printing member to print the work, and paper rupturing means operating in the direction of the line of printing to break the work an amount corresponding to a selected type line, said paper rupturing means being inoperative during the selective movement of the printing member. 120
10. A printing machine comprising a printing member having a plurality of type lines of different lengths and having two movements, one transversely of the line of printing and relatively to the platen to se- 125 130

lect a line of type and the other about an axis to move the work different distances according to the length of the selected type line to print the work, a rotary platen for co-operation with the selected type line, and paper rupturing means operating in line with the plane of rotation of the platen to break the work an amount corresponding to a selected type line, said paper rupturing means being inoperative during the selective movement of the printing member.

11. A printing machine comprising a platen, a printing member having a plurality of lines of type thereon and also having a movement out of co-operation with and independently of the platen to select one of the type lines for co-operation with the platen, paper rupturing means, and mechanism for operating the paper rupturing means to cause the latter to shift the work in the direction of the line of printing between the platen and the printing member and relatively to the printing member while the printing member and the platen are out of co-operation and for effecting automatically co-operation between the platen and the printing member after such rupturing.

12. A printing machine comprising a platen, a printing member having a plurality of lines of type thereon and also having a movement independently of the platen and out of co-operation therewith to select one of the lines of type for co-operation with the platen, a pair of rupturing rollers arranged in line with the printing line to engage the work on opposite sides, and a single controller for effecting the operation of said rupturing rollers to feed the work relatively to the printing member while the platen and the printing member are out of co-operation and for effecting co-operation between the platen and the printing member.

13. A printing machine comprising a rotary platen, a printing member having a plurality of lines of type thereon of different lengths and having two movements, one independently of the platen and out of co-operation therewith to select one of the lines of type for co-operation with the platen and the other with the rotary platen for the purpose of feeding the work, rupturing means, and means connecting the rupturing means with the platen to cause the rupturing means to be operated when the platen and the printing member are moved together and to remain stationary when the rotary printing member is moved independently of the platen.

14. A printing machine comprising a rotary platen, a printing member having a plurality of lines of type thereon and movable to cause said lines to co-operate selectively with the rotary platen, and a pair

of rupturing rollers for breaking the work in line with the line of feed, one being arranged above the work and the other below the work, the one below the work being geared to the platen and being movable about the axis of the platen as a center toward and from the rupturing roller above the work.

15. A printing machine comprising a printing member having a plurality of lines of type thereon of different lengths, said printing member having two movements, one of which is relative to the platen for the purpose of selecting one of the typed lines, a platen moved different amounts by its co-operation with the printing member on the other movement of the latter, an operating member connected to the printing member to establish co-operation between the platen and the printing member and to effect simultaneous movement of the platen and the printing member to print the work, and paper rupturing means arranged to operate in line with the printing line to rupture the work an amount corresponding to the selected typed line.

16. A printing machine comprising a printing member having a plurality of lines of type thereon and rotatable with the platen in the direction of the line of printing, said rotary printing member also having a movement independently of the platen to select a line of type, a rotary platen moved in the direction of the line of printing different distances by its co-operation with the printing member, an operating member connected to the printing member to turn the latter about its axis in order to establish connection between the printing member and the rotary platen, and paper rupturing means operable in line with the line of printing to rupture the work different amounts to correspond with the selected type line.

17. A printing machine comprising a movable platen, a printing member having a plurality of lines of type thereon and also having two movements, one of which is relative to the platen to select a type line, a platen movable simultaneously with the printing member on the other movement of said member, two paper rupturing rollers engaging the work in line with the line of printing, and a controlling member connected to the printing member to move the latter and the platen simultaneously through the co-operation of the printing member with the platen, said controlling member being unconnected with the platen during the printing, except through such co-operation between the printing member and the platen.

18. A printing machine comprising a rotary platen, a printing member having a plurality of lines of type thereon, said printing member having two movements, one in-

- dependently of the platen to select one of the lines of type for coöperation with the platen, and the other with the platen to print the work, a paper rupturing and feeding means movable to feed the work while the platen and the printing member are out of coöperation, and a single controller for the printing member and the paper rupturing means having a breakable connection between said paper rupturing means and the operating member of the printing and feeding couple, for discontinuing the feeding action of the paper rupturing means before the platen and the printing member are brought into coöperation.
- 15 19. A printing machine comprising a printing and feeding couple, movable together to feed the work in the direction of the printing line, and a paper rupturing means embodying two rollers through which the work is moved by the printing and feeding couple, one of said rollers being movable away from the other in order to permit the work to be introduced to the printing and feeding couple.
- 20 20. A printing machine comprising a platen and a printing member movable out of engagement with each other, the printing member having a plurality of lines of type thereon and also having a movement relatively to the platen for the purpose of selecting one of the lines of type for coöperation with the platen, a paper rupturing and feeding means, and a controller having connection with the rupturing and feeding means to operate the latter to feed the work relatively to the printing member in the direction of the line of printing while the latter and the platen are out of engagement, said controller also effecting engagement between the platen and the printing member to produce the printing.
- 25 21. A printing machine comprising a rotary platen and a printing member, movable out of engagement with each other, said printing member having a plurality of lines of type thereon and being movable relatively to the platen for the purpose of selecting a line of type for printing, a pair of rupturing and feeding rollers arranged in advance of the printing member and in line with the printing line, and a controller for effecting the operation of said paper rupturing and feeding rollers while the printing member and the platen are out of engagement to advance the ruptured work to the printing member, said controller also effecting the engagement between the printing member and the rotary platen to produce the printing.
- 30 22. A printing machine comprising a platen, a printing member having a plurality of lines of type thereon of different lengths and also having a movement independently of the platen to select one of the type lines for coöperation with the platen, and rupturing means for coöperation with opposite faces of the work to rupture the work in line with the line of printing and to hold the work in different adjusted positions during the selection of the type lines for successive printing operations.
- 35 23. A printing machine comprising a printing and feeding couple, an operating member for operating the printing and feeding couple to effect the printing and feeding of the work, paper rupturing means through which the work is moved by the printing and feeding couple, and connection between said paper rupturing means and the operating member of the printing and feeding couple, for causing the paper rupturing means to rupture the work and to advance the ruptured portion to the printing and feeding couple prior to the first impression. 85
- 40 24. A printing machine comprising a printing and feeding couple, operating means for operating the printing and feeding couple to effect the printing and the feeding of the work, paper rupturing means through which the work is moved by the printing and feeding couple, a breakable driving connection between the operating means of the printing and feeding couple and the paper rupturing means, and a device for breaking said connection after the rupturing device has fed a ruptured portion of the work to the printing and feeding couple and before the first impression. 95
- 45 25. A printing machine comprising a printing and feeding couple, operating means for said printing and feeding couple, paper rupturing means having two elements separable to permit the introduction of the work between them, a manually operable member for bringing the two elements of the paper rupturing device into coöperation, a breakable driving connection between the paper rupturing means and the operating means of the printing and feeding couple, said driving connection being established when the manually operable member is shifted to bring the members of the paper rupturing means into coöperation and means for automatically breaking said breakable driving connection after the paper rupturing means has shifted the ruptured portion of the work to the printing and feeding couple and before the latter have made an impression upon the work. 105
- 50 26. A printing machine comprising a rotary platen, a shaft to which the platen is secured, a printing member arranged to coöperate with the platen to feed the work, paper rupturing means having two elements 110 separable to permit the introduction of the work between them, one of said elements being rotary and geared to the shaft of the

platen, and a breakable driving connection between said platen shaft and the printing member for effecting the operation of the rotary paper rupturing element during the first part of the movement of the printing member.

27. A printing machine comprising a rotary platen, a shaft to which said platen is secured, a rotary frame, a printing wheel rotatable on the frame about an axis at an angle to the axis of rotation of the frame and adapted to coöperate with the platen to feed the work, a paper rupturing roller, a swinging frame on which the roller is mounted, said frame turning upon the platen shaft, a gear connection between the platen shaft and the paper rupturing roller, a gear mounted to move axially on the platen carrying shaft, a segmental gear carried by the rotary frame and adapted to coöperate with the gear on the platen shaft, and a device moved by the rotary frame and adapted to coöperate with the gear on the platen carrying shaft to shift the latter axially out of the path of the segment on the rotary frame.

28. A printing machine comprising a rotary platen, a shaft to which the platen is secured, a printing member arranged to coöperate with the platen to feed the work, a rotary paper rupturing device, a frame by which said paper rupturing device is carried, mounted to swing on the shaft of the platen, gearing between the paper rupturing roller and the platen shaft, and a breakable driving connection between the platen shaft and the printing member.

29. A printing machine comprising a printing and feeding couple, a paper rupturing roller, a swinging frame on which said roller is mounted, a shaft on which said frame turns, geared to said roller, and a breakable connection between said shaft and the operating means of the printing couple for stopping the feeding of the work under

the action of the rupturing device after the work is fed to the printing couple.

30. A printing machine comprising a printing member having a plurality of lines of type thereon of different lengths and having two movements, one to select lines of type for printing and the other to move the selected line for feeding the work, a platen for coöperation with the selected line of type, freely movable with the printing member through the coöperation of the type line with the platen so that the movement of the platen ceases when the end of the type line is reached and corresponds with the length of such type line, a paper rupturing means, and means connecting the paper rupturing means with the platen so that the movement of the paper rupturing means ceases when the movement of the platen discontinues at the end of the type line.

31. A printing machine comprising a platen, a printing member having a plurality of lines of type thereon of different lengths, said printing member also having a movement in order to select one of the type lines for coöperation with the platen, a paper rupturing means coöoperating with the opposite faces of the work, and means for effecting the movement of said paper rupturing means for rupturing the work an amount corresponding to the length of a selected type line.

32. A printing machine comprising a printing member having a plurality of type lines thereon of different lengths and having two movements, one to select a type line for printing and the other to effect the printing through the selected type line, and means separate from the type lines for rupturing the work on each printing operation an amount corresponding to the length of the selected type line, said means being inoperative during the selective movement of the printing member.

JOHN HEBERLING.
